TELEVISION ANTENNA

Michael D. Ercolino, Wanamassa, N. J.

Application March 20, 1950, Serial No. 8,641

Term of patent 7 years

(Cl. D26—14)

To all whom it may concern:

Be it known that I, Michael D. Ercolino, a citizen of the United States of America, residing at Wanamassa, in the county of Monmouth and State of New Jersey, have invented a new, original, and ornamental Design for a Television Antenna, of which the following is a specification, reference being had to the accompanying drawing, forming a part thereof.

In the drawing:

The figure is a perspective view of a television antenna, showing my new design.

The appearance of the antenna from the rear is substantially the same as shown by the perspective view.

I claim:

The ornamental design for a television antenna, as shown and described.

MICHAEL D. ERCOLINO.
